BY Orwig & Bair Atty's

UNITED STATES PATENT OFFICE.

DIXIE CORNELL GEBHARDT, OF KNOXVILLE, IOWA, ASSIGNOR TO THE STATE OF IOWA.

DESIGN FOR A FLAG.

57,223.

Specification for Design.

Patented Mar. 8, 1921.

Application filed December 20, 1917. Serial No. 208,181. Term of patent 3½ years.

To all whom it may concern:

Be it known that I, DIXIE CORNELL GEBHARDT, a citizen of the United States, and resident of Knoxville, in the county of Marion and State of Iowa, have invented a new, original, and ornamental Design for a Flag, of which the following is a specification, reference being had to the accompanying drawing, forming part thereof.

The figure is a front elevation of a flag illustrating my new design.

I claim:

The ornamental design for a flag, as shown.

Des Moines, Iowa, November 23, 1917.

DIXIE CORNELL GEBHARDT.
